J. A. NICHOLS

MAIL BOX

Filed May 22, 1922

UNITED STATES PATENT OFFICE.

JAMES ABRAHAM NICHOLS, OF EGAN, SOUTH DAKOTA.

MAIL BOX.

Application filed May 22, 1922. Serial No. 562,635.

To all whom it may concern:

Be it known that I, JAMES A. NICHOLS, a citizen of the United States, and resident of Egan, in the county of Moody and State of South Dakota, have invented certain new and useful Improvements in Mail Boxes, of which the following is a specification.

This invention relates to mail boxes especially adapted for use in rural districts.

10 Briefly stated an important object of this invention is to provide a mail box which can be opened by the carrier without removing his gloves or without other inconvenience.

15 A further object is to provide a rural mail box having novel means whereby the carrier may quickly observe if there is any mail in the box, thereby bringing about a substantial saving of time.

20 Also the invention forming the subject matter of this application aims to provide a mail box which is strictly weather proof, of highly simplified construction and cheap to manufacture.

25 Other objects and advantages of the invention will be apparent during the course of the following description.

In the accompanying drawing, forming a part of this application and in which like numerals are employed to designate like parts throughout the same,

Figure 1 is a perspective illustrating the improved mail box applied.

Figure 2 is a vertical transverse sectional view through the same.

Figure 3 is a detail end elevation illustrating the means for holding the box in a closed position.

30 In the drawing wherein for the purpose of illustration is shown a preferred embodiment of the invention the numeral 5 generally designates a casing which is of elongated formation and is preferably formed from sheet metal. In carrying out the in-

40 vention, one of the longitudinal sides of the casing 5 is left open for the movement of an elongated mail receptacle 6. The mail receptacle 6 is received in the casing and is pivotally supported at its ends by means of pivot elements 7. Figure 2 illustrates that the said elements 7, of which there are two, are located at the end walls of the receptacle 6 and at points spaced between the lower ends of the end walls and the sides of the same. Also the bottom of the receptacle 6 is curved transversely so that the matter

therein, such as letters or papers is highly accessible. When the receptacle 6 is swung outwardly to the position illustrated in Figure 2 the carrier may readily insert his hand into the receptacle to remove the mail therein. This may be accomplished without the carrier removing his gloves or otherwise inconveniencing himself. It will be observed that the top of the receptacle 6 is almost entirely uncovered when swung outwardly. However, the rear longitudinal edge of the receptacle 6 contacts with the top 10 and thereby limits the downward swinging movement of the receptacle. It is thus seen that the receptacle 6 is not only covered by the transversely curved top 10 but is also protected by the same.

Figure 2 illustrates that a coiled spring 12 is confined between the inner side of the receptacle 6 and the rear side 14 of the casing 5 and when the receptacle 6 is released by a means to be later described the spring 12 immediately swings the receptacle outwardly to the full line position illustrated in Figure 2. When the receptacle is swung inwardly its inward swinging movement is limited by means of stop flanges 16 formed at the ends of the receptacle and adapted to abut the vertical edges of the end walls 18 of the casing 5.

The receptacle 6 may be held in the position illustrated in Figure 1 by means of a latch 25 formed at one end of a rod or stem 26. The rod 26 is extended longitudinally of the top 10 and is rotatably connected to the same by means of staples 7 or other suitable fastening devices. One end of the rod 26 is extended laterally and is bent downwardly to provide the hook-shaped latch 25 which engages a block or projection 29 on the receptacle 6 and thereby holds the receptacle in its inner or closed position against the tension of the coiled spring 12.

The rod 26 is extended beyond the end of the casing and is extended angularly as indicated at 30 and then upwardly to provide a handle 31, the terminal portion of which is formed with a knob 32. When the knob 32 is depressed the rod 26 is rotated for elevating the hook 25 whereupon the spring 12 swings the receptacle 6 outwardly to the position illustrated in Figure 2.

In carrying out the invention the laterally projecting portion 30 is normally held in its elevated position by means of a spring 40 mounted on a stem 41 and confined between

the T-shaped attaching member 42 and a bracket 43. The bracket 43 slidably receives the stem 41 and forms an abutment for one end of the coiled spring 40 which serves to urge the knob 32 upwardly. When the knob 32 is thus urged to its elevated position the latch 25 is of course urged downwardly into engagement with the projection or enlargement 29.

10 Figure 2 illustrates that a coin and stamp receiver 48 may be located within the receptacle 6 at the rear side of the same. The front wall of the receiver 48 may be slightly cut away so as to allow ready access to the 15 contents of the same.

With reference to the foregoing description taken in connection with the accompanying drawing, it will be seen that a rural mail box constructed in accordance with this 20 invention is strictly weather proof and is provided with novel means whereby the mail may be inserted or removed without inconvenience on the part of the carrier.

In carrying out the invention the usual 25 flag or other indicating means may be employed and the box may be secured to a suitable support, such as a post 97.

Having thus described the invention, what I claim is:—

30 1. A rural mail box comprising an elongated casing having end walls and a transversely curved top, a mail receptacle of elongated formation received in said casing and having end walls pivoted to the end walls 35 of the casing, the bottom of the receptacle being curved transversely, a rod rotatably connected to the curved top of said casing and having one end extended laterally to constitute a latch adapted to engage the upper end of the receptacle to hold the same in position, a spring confined between the inner side of said receptacle and the adjacent sides of the casing, one side of said casing being open for the passage of said 45 receptacle, the curved top of said casing being arranged in the path of travel of the inner side of said receptacle whereby to limit the outward swinging movement of the receptacle.

50 2. A rural mail box comprising an elongated casing having end walls and a transversely curved top, a mail receptacle of elongated formation received in said casing and having end walls pivoted to the end walls 55 of the casing, the bottom of the receptacle being curved transversely, a rod rotatably connected to the curved top of said casing and having one end extended laterally to constitute a latch adapted to

engage the upper end of the receptacle to hold the same in position, a coiled spring confined between the inner side of said receptacle and the adjacent sides of the casing, one side of said casing being open for the passage of said receptacle, one end portion 65 of said rod being extended laterally and upwardly to constitute a handle adapted to be depressed for elevating said latch, and a spring urging said handle upwardly.

3. A rural mail box comprising an elongated casing having end walls and a transversely curved top, a mail receptacle of elongated formation received in said casing and having end walls pivoted to the end walls of the casing, the bottom of the receptacle being curved transversely, a rod rotatably connected to the curved top of said casing and having one end extended laterally to constitute a latch adapted to engage the upper end of the receptacle to hold the same 80 in position, a coiled spring confined between the inner side of said receptacle and the adjacent sides of the casing, one side of said casing being open for the passage of said receptacle, one end portion of said rod being 85 extended laterally and upwardly to constitute a handle adapted to be depressed for elevating said latch, and a spring urging said handle upwardly, and a stem connected to the laterally directed portion of said rod and extending through said spring.

4. A rural mail box comprising an elongated casing having end walls and a transversely curved top, a mail receptacle of elongated formation received in said casing 95 and having end walls pivoted to the end walls of the casing, the bottom of the receptacle being curved transversely, a rod rotatably connected to the curved top of said casing and having one end extended laterally to constitute a latch adapted to engage the upper end of the receptacle to hold the same in position, a coiled spring confined between the inner side of said receptacle and the adjacent sides of the casing, one side of said casing being open for the 100 passage of said receptacle, one end portion of said rod being extended laterally and upwardly to constitute a handle adapted to be depressed for elevating said latch, a spring urging said handle upwardly, a stem connected to the laterally directed portion of said rod and extending through said spring, and a bracket receiving said stem and constituting an abutment for one end of said 110 115

JAMES ABRAHAM NICHOLS.
